LOCOMOTIVE

Eugene L. Schellens, Ridgewood, N. J., assignor
to C-S Engineering Company, Englewood, N. J.,
a corporation of Delaware.

Application June 27, 1932. Serial No. 619,458

18 Claims. (Cl. 110—50)

This invention relates to locomotives, and is primarily concerned with the separation of cinders and other solids from the flue gases, the disposal of the separated solids, and the provision of simple structure, readily applied to existing equipment, which will accomplish these functions in such manner as to enhance the efficiency of the draft and of the locomotive as a whole.

10 The invention is, in part, a continuation of my application No. 454,020, filed May 20, 1930, on Locomotives, certain features of its subject matter being disclosed in that application.

In locomotives the present demands are for increased efficiency and great strides have already been made through economies effected in different units and appurtenances of the locomotives, for example, the average tractive power per locomotive has been increased thirty-three per cent., 20 freight train tonnage has been increased eleven per cent., freight train speeds have been increased thirty-four per cent., and the fuel consumed per freight train has been decreased thirty per cent. Similar economies have been effected in passenger service. A large majority of these economies can be traced to greater power, greater boiler capacities, the feed water heater, the superheater, the booster, and other appurtenances.

Front ends of locomotives, however, have remained practically unchanged, with the result that present standard "front ends" such as the "Master Mechanic's front end", which were satisfactory heretofore, are found to have limitations of such character that they do not meet 35 the increased demands thereon brought about by the increased efficiency of the locomotives.

It is to improvements in this part of locomotives that this invention is directed, and I aim to increase locomotive efficiency through the provision of improvements in front ends and associated mechanisms.

40 My solution of the front end problem differs from previous methods of approach in that it radically departs from the functional operation of the generally accepted front end constructions by entirely eliminating the necessity of grinding the cinders into particles small enough to pass through the screen for stack discharge. In order to properly grind up the cinders and pass 45 them through the screen or netting in these prior constructions, very high velocities are employed, with the result that the cinders come in contact with the netting a number of times and thus cause considerable wear of the netting, as well 50 as of the smokebox ring, cover, stack and other

parts. The cinders discharged through the stack have a high fuel value, and therefore a wasteage of fuel exists.

In such front ends, it is necessary that all gases pass through restricted areas under a table plate 60 and diaphragm. The energy thus consumed is a large percentage of the energy required to draft the locomotive and, in fact, approximately thirty per cent. of draft energy is consumed through 65 cinder handling and throttling due to restricted passages. This additional energy is obtained only by a corresponding increase in back pressure.

In accordance with the preferred form of my invention, I propose to separate the cinders from 70 the front end gases at low velocities and to return them to the fire box, where they are consumed. According to another form of my invention, I propose to separate the cinders by a particular arrangement of gas and cinder 75 passages. In either case, the arrangement is such that with the possible exception of occasional stray cinders and fine dust, there is no stack discharge of cinders from the front end.

Among the advantages to be obtained through 80 the practice of my invention are increased draft efficiency, operation with lower back pressure for the same draft, saving of from ten to twenty per cent. of fuel burned due to reclaiming the cinders, elimination of smoke, and increased life 85 of the front end parts. The advantages, however, extend well beyond the locomotive itself, for economies are effected in nearly every department of a railroad. These and other advantages will be better understood from the following 90 remarks.

The cinders are handled in a manner such that they gravitate to the bottom of the front end, from whence they are returned to the fire box and burned therein, so that a considerable saving of fuel is effected. Furthermore, the arrangement is such that there is substantially no loss of draft and therefore no additional energy is required. This results in a corresponding reduction in back pressure.

100 Referring particularly to the preferred form of my invention, it is pointed out that the absence of restricted passages results in an even draft distribution over the entire tube sheet of the locomotive, and tests have shown a considerably higher superheat as well as higher average evaporative values in the tube heating surfaces. Thus greater boiler efficiency is obtained.

110 The high draft efficiency obtained makes it an easy matter to control smoke conditions by

proper firing methods. This eliminates the necessity for special equipment such as has heretofore been required to reduce the smoke nuisance.

I also propose to employ a front end structure 5 of stream-line shape, and therefore, wear on the screen is very materially reduced for the cinders move in a direction tangentially along the screen rather than against it.

I also provide an arrangement whereby any 10 water which drips from the stack is drained into a water-tight well or container surrounding the exhaust pipe of the locomotive, so that as the smoke box becomes hot the water evaporates. Through this arrangement, plugging of the netting is avoided. In this connection it is pointed 15 out that in constructions such as heretofore employed, there is considerable drip from the stack under certain operating conditions which falls on the table plate, netting, or both, and often causes wetting of the cinders and netting to such 20 an extent that very objectionable soot is formed.

I further contemplate the provision of a front 25 end construction operating with relatively low velocities and with relatively low back pressures which is self-cleaning and in which the parts are arranged so that a complete inspection of the locomotive, superheater units and front tube sheet may be made without removing any internal smoke box parts.

30 By confining the stack discharge to fine dust which is blown away by even a slight breeze or washed away by rain, a substantial saving in the cost of maintaining ballast is effected.

Wherever stack exhaust containing cinders is 35 ejected directly against the surfaces of bridges, signals, tunnels, and other over-head structure, the cutting action of the cinders removes the paint or other protective coating and permits injurious gases in the stack exhaust to attack the metal. By eliminating cinders from the stack 40 discharge I not only prolong the periods between paintings, but the life of the structures themselves is materially increased.

It has also been found that live cinders ejected 45 from the stack often cause serious fire loss to property adjacent the right-of-way and, therefore, by separating the cinders from the stack exhaust I eliminate this hazard. Protection to lading along the right-of-way and in transit is also afforded.

50 Other advantages to be obtained reside in comfort and safety to passengers and employees because of the absence of cinders and smoke.

The primary object of my invention is to overcome difficulties such as mentioned above and to 55 increase the efficiency of locomotives and railroad operation in general.

Other objects have to do with improvements in the cinder return means, in locomotive firing, the 60 use of highly superheated or dry steam in returning the cinders into the fire box, and the introduction of preheated air into the fire box.

How the foregoing, together with such other 65 objects and advantages as may hereinafter appear or are incident to my invention are realized, is illustrated in preferred form in the accompanying drawings, wherein—

Figure 1 is a vertical longitudinal section 70 through a locomotive front end construction and fire box embodying my invention, with certain portions of the view broken out in order to condense the figure, and with certain of the parts appearing in elevation;

Figure 2 is a plan section taken substantially on 75 the line 2—2 of Figure 1;

Figure 3 is a view similar to Figure 1, illustrating another form of the invention:

Figure 4 is a front elevational view with the front end cover removed;

Figure 5 is an enlarged plan section taken substantially on the line 5—5 of Figure 3;

Figure 6 is an enlarged fragmentary longitudinal section at the fire box end of the form of my invention illustrated in Figure 3;

Figure 7 is a fragmentary cross section taken on 85 the line 7—7 of Figure 6;

Figures 8 and 9 are enlarged views similar to Figure 6, illustrating modifications of the invention, and

Figure 10 is an enlarged longitudinal section 90 taken substantially on the line 10—10 of Figure 5.

Figure 1 shows the front end and fire box construction of a locomotive having a boiler 1, smoke box 2, smoke box cover 2a, fire box 3, stack 4, superheater header 5, dry pipe 6, flues 7 and 8, forward flue sheet 9, rear flue sheet 9a, and exhaust nozzle 10. Between the flue sheet 9 and the stack 4 wing partitions 11 extend partially across the upper half of the smoke box. Between the inner ends of these wing partitions is the rear wall of 100 a shell 12 extending from top to bottom of the smoke box. This shell forms an inner draft chamber 13 around the exhaust nozzle 10 and the stack 4. An opening 14 is provided in the forward upper section of the shell 12 the bottom of this opening 105 being at a higher level than the bottom of the stack.

Forward of the wing partitions 11, baffle walls 15 are mounted on either side of the smoke box, 110 extending forwardly and toward but not to the center of the smoke box. These baffle or guide walls 15 are curved from side to side and are spaced from the shell 12 in such manner as to provide channels 16 around both sides of the shell. A spark screen 19 is fixed to the shell 12, completely covering the opening 14. Preferably, this 115 screen is attached to the sides of the shell in such manner as not to block the entrances of the passages 16, but it lies in said passages and extends forwardly and inwardly through and beyond them, 120 so that its sides meet in a point, as clearly shown in Figure 2, at the center line and near the front of the smoke box.

Pipes 20 are tapped into the dry pipe at either 125 side of the smoke box and extend forwardly and downwardly to cinder-receiving pockets or hoppers 21, and open into nozzles 22. Opposite these nozzles are pipes 23, each of which extends in a straight line from the cinder pocket through one of the tubes 8 to the fire box 3 (see Figure 1). 130 These pipes pass through the lower part of the passages 16, and, to protect them from the scouring action of the cinder-laden exhaust gases at these points, are covered with sleeves 23'. A straight pipe is thus provided from cinder pocket 135 to fire box, without turns or curves, so that the scouring action of the cinders passing through, will be reduced to a minimum.

The fire box 3 is provided with a mud ring 26, 140 fire arch 27 and a crown sheet 28. Mounted in the fire box between the tube sheet 9a and the arch 27 are the distributor plates 29, one opposite the end of each cinder-carrying pipe 23. The supports for these plates are tubular members 30, which may be cast integral with said plates or may be fastened thereto in any suitable manner. Slot-like channels 31 are formed in the plates 29, communicating with channels in the tubular supports 30. It will be noted that 145 150

the supports 30 project through the outer boiler shell 1 and open to the atmosphere.

In operation, the gases from the fire box pass through the flue tubes to the smoke box, below wing baffles 11, through the spaces to right and left of the shell 12 into passages 16, along and through the screen 19, through opening 14, into the inner draft chamber 13 and out through the stack. When the gases reach a point opposite the opening 14, they change their direction due to the suction created within the chamber 13 by the exhaust through the nozzle 10, and the entrained cinders are separated from the gases. The cinders fall to the bottom of the smoke box 15 and into the pockets 21.

When the locomotive is working, the cinders in the pockets 21 are blown by steam jets (supplied with steam preferably from the dry pipe 6) from the nozzles 22, into and through pipes 23, back 20 to the fire box 3. Here they are discharged upon the distributor plates 29, from which they fly off into the flame. The channels 31 serve a double purpose; first, that of carrying the plates; second, that of supplying a certain amount of 25 additional air to assist in burning the combustible elements of the cinders. Since the distributor plates are located forward of the arch, and the discharged cinders strike them at an angle and are reflected upwardly against the 30 direction of flow of the burning gases, any trouble that might be caused from the cinders being blown directly back below the arch and through the fire door, if it should be opened, is avoided.

It will be seen that the novel form and location of the screen 19 co-operate to minimize the danger of its being clogged by cinders, for most of the cinders do not come in contact with the screen, and those which do contact therewith will be carried along instead of directly against it and will be prevented from lodging in the interstices by the vertical position of the screen and by the scouring action of the gases. Although the screen may be omitted entirely, under some conditions its use is particularly advantageous in territories where low-grade fuels, such as lignite, are burned.

From the foregoing it will be seen that I am enabled to completely separate cinders and other foreign solids from the exhaust gases without impairing the effectiveness of the exhaust, and that the separated cinders are automatically and positively discharged into the fire box in such a way moreover as to prevent them from being blown back through the fire door under any circumstances.

Referring now more particularly to Figures 3, 4 and 5, which show the preferred form of my invention, the front end construction illustrated therein includes a unit A of stream-line form, associated with the stack 4a and exhaust nozzle 10a, it being pointed out that the lower stack extension extends well down into the unit A and that the exhaust nozzle 10a extends well up therein. Thus proper coordination of the stack extension and nozzle tip is afforded.

The unit A comprises a top plate 40, a bottom plate 41, a pair of curved back plates 42, and side screens 43, in this instance two screens being illustrated as making up each side. The top plate 40 is supported from the smoke box casing by means of suitable supports 44 and 45.

The particular form of smoke box 2b illustrated is provided with an arcuate recess 2c (as seen in Figures 3, 4 and 5) adjacent the stack for

receiving a feed water heater or the like, and the disposition of the unit A surrounding the stack is such that the gas-flow area between said unit and said recessed portion is approximately equal to or is greater than the flue area of the locomotive. In instances where the smoke box is provided with a flat heater recess at the top, this serves as a convenient surface for attachment of the top plate of the unit A.

The bottom plate 41 is positioned on an adapter plate 46 which is secured with a water-tight joint, as by means of welding, to an adapter member 47 located in surrounding relation to the exhaust nozzle 10a. The adapter member 47 is secured in place in the smoke box as by means of welding 85 at 48, so as to form a water-tight connection. The adapter member 47 and its plate 46 provide a means sealed from the cinder passages for collecting water drip from the stack. The drip is caught by the plate 46 and drains into the water-tight well or pocket formed by the member 47, where it is evaporated. This arrangement avoids wetting of the cinders by stack drip. The adapter plate 46 is provided with an upstanding annular flange 49 and the bottom plate 41 is provided with a depending annular flange 50 which fits inside of the flange 49. A bottom dividing plate 51 extending along the center line of the smoke box is located between the bottom plate 41 and the lower wall of the smoke box, and extends 100 from the front edge of the unit A to the adapter member 47. This dividing member may be tack-welded to the smoke box and the adapter member 47.

An upper dividing plate 52 also extending along 110 the center line of the smoke box is located between the top and bottom plates 40 and 41 and may be secured in place as by means of key and pin devices 53, and may be braced by means of braces 54. This dividing plate extends from the 115 front edge of the unit A to a point 55 spaced somewhat from the stack 4a.

Vertical frame members 56 extending from the top to the bottom plate, and horizontal frame members 57 extending from the vertical frame 120 members to the front edge of the unit, are provided, the vertical frame members being secured to the top and bottom plates as by means of pin and key devices 58, and the horizontal members being secured at one end to the vertical members 125 as by means of keys 59 and at their other ends to suitable structure 60 associated with the dividing plate 55 by means of pin and key devices 61.

The curved back plates 42, which together form 130 a semi-circular wall, are attached at their free ends to the vertical frame members 56 through the medium of cooperating lugs 62 adapted to receive pin and key devices 63; the two curved members 42 being attached together as by means 135 of hook devices 64. The sections or panels of the side screens 43 are secured in place by means of curved vertical strips 65 and curved horizontal strips 66, the strips 65 and 66 serving to clamp the screen panels against the vertical frame members 56, the horizontal frame members 57 and the structure 60, which is carried at the dividing plate 52. The clamping is effected by means of pin and key devices 67. It is to be noted that the top edge portions of the upper screen panels rest 145 against flanges 68 provided on the top plate 40, and that the lower edge portions of the bottom screen panels rest against similar flanges provided on the bottom plate 41.

A dividing plate extension 70 is secured to the 150

front edge portion of the dividing plate 52 and has its front edge configured to conform with the inside of the front smoke box cover, a slight space 71 being provided between the front edge of the 5 plate and the inside surface of the smoke box cover. This extension may be secured to the dividing plate 52 by means of bolts and double nuts.

It will be noted that the dividing plates 51 and 52 and the extension 70 serve to divide the front 10 portion of the smoke box into halves, in which cinders collect. These plates also function to prevent cross-currents from one side or half of the smoke box to the other, so that no eddies or vortexes are set up. By eliminating the eddies and 15 vortexes, increased efficiency is obtained and objectionable churning around of the cinders is prevented. I prefer to have the bottom edge 72 of the extension 70 located at a point somewhat above the bottom wall of the smoke box, so that 20 a relatively small opening 72a is provided at the bottom through which cinders may pass from one half of the smoke box to the other half.

Referring particularly to Figure 4, it will be 25 seen that the size of the unit A is such that comparatively large and unrestricted passages are provided at each side thereof for the free passage of the gases and cinders, so that low velocity operation is obtained. The cross-sectional area of these passages may be from one hundred 30 and fifty per cent. to two hundred per cent. of the flue area.

As will be seen from inspection of Figure 5, the rounded back wall and the side screens arranged in the form of a V cooperate to provide a 35 stream-line device. This stream lining goes hand in hand with the low velocities in increasing the effectiveness of the device.

The unit A may be readily applied to existing 40 smoke boxes, since it merely replaces the conventional type of netting and baffles. The unit is readily assembled due to its simplicity of construction involving removable plates conveniently joined together by strips and key devices.

In the lower portion of the smoke box and to 45 each side of the unit A, a pair of cinder return pipes 23a are located. These pipes, as in the form illustrated in Figures 1 and 2, extend from the smoke box to the fire box and are straight from their entrance ends to their exit ends and extend 50 through lower flues 8a of the locomotive boiler. Each cinder return pipe 23a is preferably made of two sections 23b and 23c. The section 23b, which is at the smoke box end of the pipe, has a thicker wall than the other section 23c, but the inside diameters of the two are the same. The section 23b is preferably readily replaceable.

An ejector device 73 is associated with each 55 cinder return pipe 23a at its entrance or smoke box end, and since the pipes are located low in the smoke box, the ejector devices will be submerged in the cinders collecting in the bottom thereof. Each device 73 includes a steam nozzle 74 and a supporting member 75 (see Figure 10). The supporting member 75 is provided with a steam chamber 76 to which steam is admitted by means of a steam inlet 77. Steam pipes 78 lead steam to the steam chambers 76 of the ejector devices 73 from the main steam pipes 79 of the locomotive. Check valves 80 are provided in the steam pipes 78 to prevent cinders from being sucked back 70 through the steam pipes when drifting due to high vacuum in the main steam pipes 79.

By arranging the steam supply pipes 78 in the manner just described, the supply of steam to the 75 ejector devices is synchronized with the main

throttle of the locomotive, and therefore, the steam supply to the steam ejectors is always closed when the main throttle is closed. In some instances, however, it may be desirable to have the steam pipes 78 receive their steam from the steam dome of the locomotive. In such case, a special superheater unit is provided to which saturated steam is led from the dome, and from which the superheated steam is led to the ejector devices. I also propose in some instances to take the steam from the superheated side of the superheater at the main blower pipe. Although with these arrangements steam would continuously blow through the ejectors, whether the locomotive throttle be closed or not, they nevertheless have certain operating advantages. For example, the latter arrangement causes circulation through the superheater at all times.

At the end of the supporting member 75, opposite the steam chamber 76 and axially spaced therefrom, is a ring-like portion 81 (see Figure 10) having an aperture 82 therein for receiving the section 23b of the cinder return pipe 23a. The aperture 82 is in coaxial alignment with an aperture 83 in the wall 84 of the steam chamber 76, which aperture is adapted to receive the steam nozzle 74. The steam chamber and the ring-like portion 81 are connected together by means of a pair of arms or webs 85. These arms are preferably diametrically oppositely disposed 105 in a horizontal plane so that cinders may freely pass to the space therebetween from the top and bottom. By so disposing these arms, arching of the cinders between them is prevented. Stated in another way, the connecting arms 85 are arranged to constitute a cage-like supporting means for the ejector and return pipe of such character that cinders may freely enter the entrance end of the cinder pipe. In order to support the cinder return pipe assemblies at the smoke box end, 110 brackets 23d are employed at spaced intervals along the portions thereof which extend into the smoke box, the brackets being secured to the smoke box casing. The support of these pipes at the fire box end will be described hereinafter.

It will thus be seen that I have provided a construction whereby the steam nozzle 75 may be solidly supported from the cinder return pipe and in exact coaxial alignment therewith. This is of 115 utmost importance to the proper functioning of the device, for I have found that if the cinder pipe and the ejector are ever so slightly out of alignment, the cinder pipe will wear out very rapidly. This would also be true if the cinder pipe were to have any bends therein or if obstructions of any kind were to be in the path of the stream of steam and cinders passing through the pipe. It will thus be seen that it is of importance not only to have the ejector and cinder pipe in absolute alignment but also to employ a pipe 125 which is straight from its entrance to its exit end, with no obstructions of any kind therein.

By spacing the steam nozzle away from the entrance end of the cinder pipe and submerging the ejector device in a body of collected cinders, 130 it will be seen that the cinders are ejected into the pipe with the steam, and therefore objectionable abrasion such as would occur if the cinders were induced into the pipe by a steam nozzle located within the pipe at its entrance end, is avoided.

In explanation of the above, it is pointed out that the steam jet at the entrance end of the cinder pipe has a spread of approximately eight per cent. or one inch in twelve inches. The steam jet, of course, produces an entraining effect on 135

the surrounding gases and effects a heavy flow of cinders into the entrance of the pipe. All of these cinders must at some time pass into the steam jet and some of them contact with the jet before entering the pipe, while a large proportion thereof are whirled through the pipe so that they do not touch it, except possibly at some point way back, and then only at a very small angle of incidence. In fact, some of the cinders do not touch the pipe at all. Experience shows that any wear which may occur is greatest at approximately nine to twelve inches from the entrance end of the pipe, or around the point where the jet first contacts with the pipe. As pointed out above, this portion or section of the pipe is heavily walled and it is found that any wear taking place thereat results in producing a gradual concaving of the interior of the pipe apparently of the contour of the spreading jet, whereupon the rate of wear rapidly decreases. The wear is slight, and no doubt is caused only by the finer dust, as the heavier cinders are mostly carried well back of this point due to their momentum. I further attribute the absence of any appreciable wear to the presence of eddies due to resistance, at the edge portion of the stream of steam where the steam contacts with the pipe, these eddies probably being in the form of backward curls rejoining the main body of the stream. If this be the case, the cinder particles as they are entrained in the steam stream when they reach the periphery of the stream, come into the region where the eddies are and where their velocity relation to the pipe wall is much reduced, so that even if impingement occurs, it is so slight that the abrasive action is negligible.

If there should be a slight misalignment of the nozzle and pipe, this eddy condition would be different and the cinder particles would forcefully impinge and have a scouring action. Stated in another way, with such misalignment, the entire mass of cinders is directed to a small portion of the pipe, resulting in concentrated wear as well as an increase in the angle of incidence.

I have found that while wear takes place at the initial point of contact, the amount thereof decreases rapidly after initial service of the device, and this no doubt is due to the greater surface over which this wear is distributed and to some change in the angle of incidence of the particles contacting with the surface. In general, it may be stated that for a given cinder velocity and mass, the cinder wear will be a function of the angle of incidence against the pipe wall. Actual operation has shown that a device constructed in accordance with my invention operates in a manner such that difficulties heretofore experienced with cinder pipes wearing out, are overcome.

By arranging the cinder return pipes within boiler flues and by employing superheated or dry steam in the ejectors, the cinders are prevented from becoming moisture-laden. In this connection it is pointed out that if the cinder return pipes were located directly in the water space of the boiler, they would sweat when the locomotive is being fired up, for example, and difficulties such as plugging up of the pipes would be encountered. Similar difficulties would be encountered if saturated steam were used in the ejectors.

Referring now to the fire box end of the locomotive, it will be seen that the axes of the cinder return pipes extended, fall below the fire box arch. In the form of fire box illustrated at 3a in Figures 3 and 6, each cinder return pipe 23a is

provided with an extension tube 86 which serves to extend the cinder return pipe from the rear tube sheet 9b into close proximity to the fire box arch 27a. An air flue 87 is mounted on the extension tube 86 in spaced surrounding relation thereto and is preferably covered with heat-resisting lagging 88. A solid centering bushing 89 is employed at the flue sheet end of the air flue and a plurality of centering lugs 90 are employed at the other end thereof. An air duct 91 fitting within a sleeve 92 is provided for leading atmospheric air to the interior of the air flue 87. The sleeve 92 is welded to the boiler shell 93 and to the fire box shell 94, and the air duct 91 is welded to the sleeve 92 at one end and has a snug fit at its other end into an aperture in the wall of the air flue 87. Spaced blocks 95 carried by the fire box shell 94 are provided for supporting the air flue and cinder pipe extension. It is to be noted that the cinder pipe 23a is supported at its end portion 96 by the structure just described.

I prefer to employ special arch bricks 97 having apertures 98 in coaxial alignment with the cinder return pipes through which apertures the cinders and carrying steam are discharged into the fire box below the arch thereof.

In operation, the atmospheric air in passing through the air flue 87 is preheated, so that pre-heated air is introduced into the fire box with the cinders and steam. The air flue 87 acts as an air cooling means for the cinder pipe extension, and therefore protects it against burning out due to the heat within the fire box.

In Figure 8 I have illustrated a modified arrangement of the above applied to a fire box 3b of a different type. In this construction the cinder pipe extension 86a is considerably shorter than that shown in Figure 6, and the air flue 87a is supported directly from a pair of air ducts 91a which are attached at their upper ends to the air flue and at their lower ends to a fixed plate 99. An upright wall 100 is associated with the fire box arch 27b and is provided with an aperture 101 in coaxial alignment with the cinder return pipe through which the cinders carrying steam and heated air are introduced into the fire box.

In Figure 9 I have illustrated a fire box construction 3c of a type in which the arch tubes 27c of the fire box arch are so relatively disposed with respect to the flue sheet that no extension 125 is needed on the cinder return pipe 23c. In this instance the cinder return pipe ends substantially at the flue sheet and discharges its cinders and steam through an aperture 98a in the special arch brick 97a.

Through the arrangements just described, even distribution of the cinders in the fire box is obtained.

The cinder return pipe assemblies which include the ejector devices 73, the thickened wall 135 pipe section 23b and the pipe section 23c, are handleable as a unit and may be readily removed as such through openings 102 provided in the front cover of the smoke box. These openings may be closed by means of plugs 103. It will 140 thus be seen that the cinder pipe assemblies may be removed without disturbing the smoke box front. In the event that one of the cinder ejector devices goes out of order, the remaining one will handle the cinders. In such a case, collected cinders will pass from one half of the smoke box to the other through the opening 72a at the bottom of the dividing plate.

It will be seen from the foregoing that by handling the cinders in the manner described and 150

returning them to the fire box where they are burned as fuel, I have in effect provided what may be termed a secondary stoker for the locomotive, which handles fuel taken from within the locomotive system.

No specific claim is made herein to the cinder separating means in the smoke box illustrated in Figures 1 and 2 of the drawings, as claims directed thereto form part of the subject matter of my copending applications Serial No. 415,199, filed December 19th, 1929, and Serial No. 454,020, filed May 20th, 1930. No specific claim is made herein to the cinder separating means in the smoke box illustrated in Figures 3, 4, 15 and 5 of the drawings, as claims directed there- to form part of the subject matter of my copending application Serial No. 674,793, filed June 8th, 1933, which application is a division of this case.

20 I claim:

1. In a locomotive having a boiler, a smoke box, and a fire box, means for returning cinders from the smoke box to the fire box including an open ended unobstructed return pipe straight from end to end and extending from smoke box to fire box, one open end of which constitutes a cinder entrance and the other a cinder exit and a fluid operated cinder ejector in coaxial alignment with said pipe and exterior thereof at its entrance end.

2. In a locomotive having a fire box, a smoke box adapted to collect cinders, means for transporting cinders from the smoke box to the fire box including an open ended unobstructed return pipe straight from end to end and extending from smoke box to fire box, the open end at the smoke box constituting a cinder entrance and the other open end a cinder exit, and an ejector mounted in coaxial alignment with and in spaced relation to said pipe at its entrance end to provide a space therebetween from which cinders are ejected into and thru the pipe.

3. In a locomotive having a fire box, a smoke box adapted to collect cinders, means for transporting cinders from the smoke box to the fire box including an open ended unobstructed return pipe straight from end to end and extending from smoke box to fire box, the open end at the smoke box constituting a cinder entrance and the other open end a cinder exit, and an ejector mounted in coaxial alignment with and in spaced relation to said pipe at its entrance end, said pipe being so located that its entrance end and the associated ejector are in the lower portion of the smoke box.

4. In a locomotive having a boiler, a smoke box, and a fire box, means for returning cinders from the smoke box to the fire box including an open ended unobstructed return pipe straight from end to end and extending from smoke box to fire box, one open end of which constitutes a cinder entrance and the other a cinder exit, and a cinder ejector supported from said pipe at its entrance end in coaxial alignment therewith.

5. In a locomotive having a boiler shell, a smoke box and a fire box, means for returning cinders from the smoke box to the fire box including a straight pipe located within the boiler shell and an ejector supported from said pipe, said means being insertable and removable as a unit.

6. In a locomotive having a boiler, a smoke box, and a fire box, means for returning cinders from the smoke box to the fire box including an open ended unobstructed return pipe straight from end to end and extending from smoke box

to fire box, one open end of which constitutes a cinder entrance and the other a cinder exit, a cinder ejector, and means for supporting said ejector from said pipe in coaxial alignment therewith and in spaced axial relation thereto.

7. In a locomotive having a smoke box and a fire box, means for returning cinders from the smoke box to the fire box including a straight pipe, an ejector, and means for supporting the ejector from the pipe in coaxial alignment therewith and in spaced axial relation thereto including spaced elements for supporting the ejector from the pipe, and means connecting said elements, said means being spaced to prevent arching of cinders.

8. In a locomotive having a smoke box, a boiler, a fire box, and a superheater, means for returning cinders from the smoke box to the fire box including a return pipe extending from the smoke box to the fire box, a superheated steam operated cinder ejector associated with said pipe, and means for leading operating steam to said ejector from the superheater.

9. In a locomotive having a smoke box, a boiler, a superheater, a fire box, and flues extending between smoke box and fire box through said boiler, means for returning cinders from the smoke box to the fire box including an open ended return pipe straight from end to end and extending from said smoke box through one of said flue tubes to said fire box, a superheated steam operated cinder ejector in coaxial alignment with said pipe at its entrance end and means for leading operating steam to said ejector from said superheater.

10. In a locomotive having a fire box, a pipe extending into said fire box for the discharge of cinders thereinto, and means for introducing preheated air into said fire box with the cinders, said means including an air preheater in sur- rounding relation to said pipe.

11. In a locomotive having a fire box, a pipe extending into said fire box for the discharge of cinders thereinto, a jacket in spaced surrounding relation to said pipe and having openings discharging air into the fire box and means establishing communication between the interior of the jacket and the atmosphere.

12. In a locomotive having a fire box, a pipe extending into said fire box for the discharge of cinders thereinto, a jacket in spaced surrounding relation to said pipe, means for supporting said jacket, said means being hollow and establishing communication between the atmosphere and the interior of the jacket, and said jacket having an outlet establishing communication between its interior and the fire box.

13. In a locomotive having a smoke box and a fire box, means for returning cinders from the smoke box to the fire box including a straight pipe and an ejector in coaxial alignment with said pipe at one end thereof, said pipe having a thickened wall portion at its ejector end.

14. In a locomotive having a smoke box and a fire box, means for returning cinders from the smoke box to the fire box including a straight pipe, and an ejector in coaxial alignment with said pipe at one end thereof, said pipe having a detachable thickened wall portion at its ejector end.

15. In a locomotive having a smoke box, a boiler, a fire box, and flues extending between smoke box and fire box through said boiler, a cinder collecting compartment in the lower portion of the smoke box directly open to the smoke box

- space, and cinder removing means extending from said compartment through one of said flues to the fire box, said means including an open ended unobstructed return pipe straight from end to end and extending from the cinder collecting compartment to the fire box, one open end of which constitutes a cinder entrance and the other a cinder exit, and a fluid operated cinder ejector in coaxial alignment with said pipe and exterior thereof at its entrance end. 5 80
16. In a locomotive having a smoke box, a boiler and a fire box, means for returning cinders from the smoke box to the fire box including a plurality of open ended unobstructed return pipes straight from end to end, means providing a plurality of cinder collecting compartments in the lower portion of the smoke box in direct open communication with the smoke box proper, said return pipes extending from said compartments to the fire box, one open end thereof constituting a cinder entrance and the other a cinder exit, and a fluid operated cinder ejector in coaxial alignment with each return pipe at its entrance end. 10 85
17. In a locomotive having a smoke box, a boiler and a fire box, means for returning cinders from the smoke box to the fire box including a 15
18. In a locomotive having a smoke box, a boiler and a fire box, means for returning cinders from the smoke box to the fire box including a plurality of open ended unobstructed return pipes straight from end to end, means providing a plurality of communicating cinder collecting compartments in the forward lower portion of the smoke box in direct open communication with the smoke box proper, said return pipes extending from said compartments to the fire box, one open end thereof constituting a cinder entrance and the other a cinder exit, and a fluid operated cinder ejector in coaxial alignment with each return pipe at its entrance end. 20 90
